UNITED STATES PATENT OFFICE

135,425

DESIGN FOR AN ALIGNING AND HOLDING BRACKET FOR PLATE WELDING OPERA- TIONS

Roy W. McLaren, Oaklyn, N. J.

Application February 9, 1943, Serial No. 109,508

Term of patent 14 years

To all whom it may concern:

Be it known that I, Roy W. McLaren, a citizen of the United States, residing at Oaklyn, in the county of Camden and State of New Jersey, have invented a new, original, and ornamental Design for an Aligning and Holding Bracket for Plate Welding Operations, of which the following is a specification, reference being had to the accompanying drawing, forming part thereof.

Figure 1 is a side elevation of an alining and

holding bracket for plate welding operations, showing my new design.

Figure 2 is a front elevation, that is, a view at right angles of Figure 1.

Figure 3 is a perspective view of the same.

I claim:

The ornamental design for an alining and holding bracket for plate welding operations, as shown.

ROY W. McLAREN.
